ICE REMOVAL TOOL

Ray W. Reed, 2075 Richwood Drive,
Pontiac, Mich. 48057

Filed Dec. 10, 1969, Ser. No. 20,431

Term of patent 14 years

Int. Cl. D8—02

U.S. Cl. D8—14

FIG. 1 is a front elevational view of the ice removal tool shown in FIG. 2 as seen from the right side of FIG. 2;

FIG. 2 is a side elevational view of the ice removal tool shown in FIG. 1;

FIG. 3 is a reduced perspective showing of the tool seen in FIGS. 1 and 2 in an inverted position; and

FIG. 4 is an enlarged face elevational view of the strainer portion of the tool seen in FIGS. 1, 2 and 3 taken in the direction of arrow 4 in FIG. 2.

I claim:

The ornamental design for an ice removal tool, as shown.
